UNITED STATES PATENT OFFICE.

JOHN E. EVILSIZOR AND CARL FOLLRATH, OF SPRINGFIELD, OHIO.

ORNAMENT-SUPPORT.

1,344,027.

Specification of Letters Patent. Patented June 22, 1920.

Application filed June 2, 1919. Serial No. 301,267.

To all whom it may concern:

Be it known that we, JOHN E. EVILSIZOR and CARL FOLLRATH, citizens of the United States of America, residing at Springfield, 5 in the county of Clark and State of Ohio, have invented new and useful Improvements in Ornament-Supports, of which the following is a specification.

This invention relates to ornamentations 10 and comprehends the provision of a device primarily intended as a substitute for cedar trees, designed for the purpose of hanging ornaments therefrom.

The characteristic of the invention resides 15 in the provision of a device of the above mentioned character having a substantially bell shaped outline and covered with material to add to the ornamentality of the same, the invention being constructed to be 20 collapsed and thus occupy a minimum of space when not in use.

The nature and advantages of the invention will be better understood when the following detailed description is taken in connection with the accompanying drawing, the invention residing in the construction, combination and arrangement of parts as 25 claimed.

In the drawing forming part of this specification, like numerals of reference indicate 30 similar parts in the several views and wherein:—

Figure 1 is a perspective view of the device forming the subject matter of our invention.

Fig. 2 is a plan view showing the same in collapsed condition.

The device forming the subject matter of our invention essentially consists of a plurality of annuli arranged in superimposed relation, and successively increasing in diameter from the uppermost to the lowermost annulus as shown. The annuli may be constructed from any suitable material, 40 preferably wire, and covered with colored material such as paper, cloth or the like, to add to the ornamentality of the device as a whole. The annuli are connected with a plurality of flexible elements 11 which are arranged to give the device a configuration 45 similar to that of a bell. The flexible element 11 may be of any suitable material and of the same color or of a different color

from the material which covers the annuli. All of the flexible elements 11 have their 55 corresponding upper extremities brought together and secured to the eye 12 of a member utilized to suspend the device from a suitable support. The member of which the eye 12 forms a part terminates at one end to 60 provide a hook 13. It is to be understood that any number of annuli may be employed to vary the size of the device. Suspended from each annulus is a plurality of small rings 14 upon which ornaments of any suitable character may be supported. As above 65 stated, the device is intended as a substitute for cedar trees and can be used without making as much dirt as the tree, and by reason of the flexible connections between 70 the annuli, the device may be collapsed in the manner shown in Fig. 2 to minimize space when its use is not desired. Consequently the device can be packed in a suitable 75 box and kept from year to year.

While we have shown and described what we consider the preferred embodiment of the invention, we desire to have it understood that we do not limit ourselves to the exact construction and arrangement, as such 80 changes may be resorted to when desired as fall within the scope of what is claimed.

What we claim is:—

A substantially bell shaped article support comprising in combination, a plurality 85 of spaced superimposed rings successively increasing in diameter from the uppermost to the lowermost ring, an ornamental covering for each ring, flexible elements connecting all of said rings at the peripheries thereof, and supporting the rings in spaced relation for permitting the device to collapse with the rings one within the other, said flexible supporting elements being of the same material as the covering for said rings, 90 a circumferential series of eyes depending from each ring, a supporting hook having a terminal, and all of said flexible elements having their upper extremities brought together at a point centrally of the uppermost 95 ring, and secured in said terminal as described.

In testimony whereof we affix our signatures.

JOHN E. EVILSIZOR.
CARL FOLLRATH.
